UNITED STATES PATENT OFFICE.

DANIEL HENRY MEYER, OF ELKVILLE, ILLINOIS.

DIPPER TOOTH.

Application filed August 6, 1928. Serial No. 297,758.

This invention relates to an improved tooth construction, for steam shovel dippers, and it has more particular reference to the species of tooth commonly known in the trade as a two-part tooth, that is, one which is composed of relatively stationary teeth or bodies riveted to the dipper front, and renewable points carried thereby.

The object of the two part tooth is that the point can be removed and a new one attached, without disturbing the base. This being done, the tooth is again as it was when new, for the point of the tooth takes nearly all of the wear when the dipper is digging. I am aware that numerous types of two part teeth have been designed from time to time to accomplish this desirable result and that the parts of the tooth are held together in much the same way, usually by a bolt or pin passing through the point and the base.

Having in mind the huge steam and electric shovels employed at strip mines and quarries, at the present time, and bearing in mind that the point is still held to the base by a bolt or pin, much the same as the original two part tooth, after a week or ten days of digging in shale, and rock, we find that where the larger shovels are used, the digging tooth is no longer a sharp cutting tool, but rather a blunt stump. In removing this point, we find the pin or bolt which holds it to the base is sheared so that it cannot be driven out. It must then be cut out with a torch before it can be removed. After the point is removed, we find we have a manganese steel or other high grade steel casting, which is unfit for further use, although less than five per cent of it has been worn away. This point is far too large for the blacksmith to sharpen and treat, and the result is that it is discarded in the scrap pile.

Often the bolt holding the point breaks, or the bolt hole in the point breaks allowing the point to become lost. Frequently the point is lost among the rock, shale and dirt seldom recovered. Having experienced these difficulties, I have discovered the need for a revised structure which is more dependable and capable of fulfilling the requirement of a structure of this class which is subject to such severe treatment. I have therefore provided a relatively small appropriately sharpened and shaped point which is a point, rather than one quarter of

a dipper tooth, one which does not depend upon a bolt or pin to hold it to the base but has a large shear annulus on each side for this purpose, one which is properly braced against any stresses or strains that can be applied to the tooth, a structure which is not too large to be sharpened and treated by the average blacksmith, but something which it is believed is an advancement in the art.

In the drawings:

Figure 1 is an elevational view of a shovel dipper, equipped with an improved two-part tooth constructed in accordance with the present invention.

Figure 2 is a top plan view of the tooth. 70

Figure 3 is a side elevation view thereof.

Figure 4 is a cross sectional view, taken approximately upon the plane of the line 4—4 of Figure 10.

Figure 5 is likewise a cross section taken 75 on the plane of the line 5—5 of Figure 10.

Figure 6 is a similar sectional view, taken on the plane of the line 6—6 of Figure 9.

Figure 7 is a detail view of the tapered retaining pin. 80

Figure 8 is a longitudinal section taken approximately on the plane of the line 8—8 of Figure 3.

Figure 9 is a side elevation of the point disconnected from the base or body. 85

Figure 10 is a fragmentary side elevation of the especially designed base.

Figure 11 is a detail view of a coupling plug, constituting an important factor of the invention. 90

Referring now to Figure 1 of the drawings, it will be seen that 12 designates generally an ordinary dipper, such as is employed on steam and electric shovels of the character used at strip mines and quarries. This is provided on its front with a number of two part teeth, each of which is identical in construction. As before intimated, each tooth comprises a body or base portion 13 which as better shown in Figure 3, is bifurcated, so that the furcations are permitted to straddle and be riveted or otherwise fastened to the dipper. 95

In accordance with the invention, the body is constructed as shown better in Figure 10, wherein it will be observed that it is provided with a reduced extension 14, having a further reduced terminal 15. The ex- 100 105

tension 14 is provided in opposite faces with circular pockets 16, and recesses 17 cooperable with bridging keepers 18.

The portions 14, 15 and 16 are adapted for reception in the scored out portion of the point 19. The point is of tapered design and is comparatively small when considered alongside of the average point employed today in work of the character stated. This 10 point is provided on its enlarged inner end with projecting lugs 20, receivable in the recesses 17 and underneath the keepers 18, as shown in Figure 8. The recessed portion has its wall formed with openings 21 adapted to 15 register with the sockets 16 to accommodate the coupling plugs 22. Incidentally the plugs are of dish like construction and each plug is formed with a central stem 22', having a groove 23, to accommodate the tapered 20 retaining pin 24. Attention is now invited to an exceptionally important factor in the present invention, namely the means provided on the point 19 for preventing shearing and breaking of the retention pin 24. 25 The means is duplicated on opposite sides of the point as shown in Figure 8. It comprises, in each instance, an annular outstanding rim 25 having diametrically opposite openings for accommodation of the pins, and 30 extending from the openings are projections 26, constituting guides as well as guards.

With this arrangement, it is obvious that the recessed or socketed portion of the part 19 is simply fitted over the extension 35 14, on the body 13, so that it occupies the connected relationship shown in Figure 8. Then the plug 21 drops down through the annular rim or guard 25, into the socket 16, and the plug is turned so that the 40 grooves 23 register with the pin receiving opening in the rim. Next the wedge pins are driven in, and through the grooves 23, thus holding the plug 21 in place, and effecting a sturdy coupling between the point 45 and the extension 14. Thereafter, the pins

are protected by projecting annuli, and when it becomes necessary to remove the point to be sharpened, it is an easy matter to knock out the pins to permit the removal of the point.

It is though that the advantage, the construction, the method of application and use and the merits of the invention will be quite clear after considering the description of the invention in connection with the drawings. Therefore a more lengthy description is regarded unnecessary.

I claim:

1. A two part tooth of the class described comprising a body having an extension at 60 one end provided with a socket, a point having a recess for reception of said socketed extension, one wall of said recess having an opening in registry with the socket, a plug removably received in said 65 socket and opening and effecting a coupling between the point and extension, and removable retaining means for the plug mounted on the point, said retaining means comprising a pin, said plug having a 70 grooved portion for reception of the pin.

2. A two part tooth of the class described comprising a body having an extension at one end provided with a socket, a point having a recess for reception of said socketed extension, one wall of said recess having an opening in registry with the socket, a plug removably received in said socket and 75 opening and effecting a coupling between the point and extension, and removable retaining means for the plug mounted on the point, 80 said retaining means comprising a pin, said plug having a grooved portion for reception of the pin, together with an annular 85 outstanding rim mounted on said point and surrounding said opening, said rim having holes for passage of the retaining pin.

In testimony whereof I affix my signature.

DANIEL HENRY MEYER.
